UNITED STATES PATENT OFFICE.

THOMAS E. GOULD, OF BROOKLYN, NEW YORK

FURNITURE-CASTER.

1,102,149.

Specification of Letters Patent. Patented June 30, 1914.

Application filed November 4, 1913. Serial No. 799,133.

To all whom it may concern:

Be it known that I, THOMAS E. GOULD, a citizen of the United States, residing at Brooklyn, in the county of Queens and State 5 of New York, have invented certain new and useful Improvements in Furniture-Casters, of which the following is a specification.

This invention relates to improvements in furniture casters.

10 The invention has for its object to provide a caster of the aforesaid type which shall be practically unbreakable in use.

A further object is to reduce friction to the minimum in the swiveling action of the 15 caster.

A still further object is to facilitate the swiveling action of the caster, also to expedite the application or attachment thereof to the article in connection with which it is 20 used.

The invention therefore consists of the detailed structural features substantially as hereinafter fully disclosed and defined by the appended claim.

25 In the accompanying drawing is illustrated the preferred embodiment of my invention wherein it will be understood that various changes and modifications as to the detailed construction and arrangement of 80 parts may be made without departing from the spirit of the invention, and in which drawing—

Figure 1 is a side elevation of my caster. Fig. 2 is a vertical section of the same taken 35 centrally about therethrough and transversely to and at one side of the caster-wheel axis, said caster-wheel with a portion of its carrying bracket being removed. Figs. 3 and 4 are inverted disassembled perspective views showing more particularly the annular race-forming portions of the caster-wheel and attaching members of the device.

In carrying out my invention, I form the same of two castings, one of which, designated as 1, may be termed as the caster-wheel bracket-carrying member, and the other of which, designated as 2, may be termed as the attaching or base member, the two conjointly constituting a "turn-table" 50 like arrangement. The member 1 includes an annular or disk-like portion 3 and opposed pendant-arms or bearings 4 between which is received or carried the caster-wheel 5, the axle 6 of which is journaled in said 55 arms or bearings. The disk or member 1

has an annular recess or chamber 7 in its upper surface, the wall 8 of which is perpendicular upon its inner surface, while its outer surface is tapered or beveled from the outer edge or perimeter of the disk-forming portion of the member 1 inwardly and downwardly as at 9, thus thickening and accordingly reinforcing said wall against liability of breakage. The member 1 also has a central opening or aperture 10 there-through, the purpose of which will presently be apparent.

The member 2, which is suitably provided with preferably countersunk apertures 11 at its corners to receive the attaching screws 70 or fastenings (not shown), has formed in its lower surface also an annular recess or chamber 12 to receive the annular wall 8 of the recess or chamber 7 of the member 1 within which recess or chamber 12 the latter 75 turns, the upper edge of said wall bearing upon the bottom of the chamber 12; in other words the wall 8 of the recess or chamber 7 telescopes the wall of the chamber or recess 12 of the member 2, the same thus constituting 80 a turn-table like arrangement, as will more fully appear presently.

Concentrically arranged within the recess or chamber 12 of the member 2, and integral with the bottom of said chamber, is an annular protuberance 13, and interiorly of the latter and spaced off therefrom is also formed upon the bottom of said chamber 12 a hub-like pivot 14 which is somewhat flared toward its base and which forms with said annular protuberance an annular depression or race 15 suitably furnished with a plurality of bearing balls 16 to provide a practically frictionless and sensitive bearing for the caster-wheel bracket at this point. The 95 inwardly flared and accordingly outwardly tapered pivot 14 extends through the aperture or orifice 10 of the member 1, which aperture snugly receives said pivot and whereby it is apparent lateral unevenness 100 of movement or wobbling of the caster-wheel carrying bracket is prevented.

A rivet-like member or pin 17 is inserted through the tubular pivot 14 and suitably held in effective position to effect connection 105 between the two members 1 and 2, one end of the pin, or rivet being formed with a head previous to its insertion and the other end of said rivet being subsequently headed to prevent its displacement, said pin or 110

rivet-like connection being such, however, as not to interfere with the swiveling action of the caster-wheel carrying bracket.

It is believed that from the foregoing disclosure the advantages and facilities of my invention as set forth in the introductory clauses to the description have been made fully apparent and that the same therefore needs no further elaboration.

10 herein.

I claim—

15 A caster of the type described, including two members, one member having a rim-edge annular portion and a central tubular portion extending through a central orifice of the second member, said central tubular portion receiving and having applied thereto retaining means for said second member,

said first-referred to member having a second annular portion depending therefrom 20 intermediate said rim-edge annular portion and said central tubular portion to form with the latter an annular depression, said second member having an annular portion received between said rim-edge annular portion and said second annular portion of the first-referred to member, and rotary bearing members contained within said annular depression of the first-referred-to member.

25 In testimony whereof I affix my signature 30 in presence of two witnesses.

THOMAS E. GOULD.
